UNITED STATES PATENT OFFICE.

BENJAMIN F. GABLE, OF SAN FRANCISCO, CALIFORNIA, ASSIGNOR OF ONE-HALF TO
JOHN M. LETTICH, OF SAN FRANCISCO, CALIFORNIA.

DISCHARGE-NOZZLE AND CONTROLLING MEANS THEREFOR.

1,210,630.

Specification of Letters Patent.

Patented Jan. 2, 1917.

Application filed June 8, 1915. Serial No. 32,941.

To all whom it may concern:

Be it known that I, BENJAMIN F. GABLE, a citizen of the United States, residing in the city and county of San Francisco and 5 State of California, have invented certain new and useful Improvements in Discharge-Nozzles and Controlling Means Therefor, of which the following is a specification.

The present invention relates to improvements in the construction of the water inlet mechanism for flushing tanks or the like, and has for its objects to provide a valve structure which when closing will shut off the inflow of water into the tank without 10 the hammering or noise which is present in the devices now generally in use.

While the present invention is illustrated in connection with the inlet of flushing tanks, it is to be understood that the same 20 is equally as well adapted for use in all structures where the stream flow is desired to be controlled or diffused.

The invention consists primarily in the employment of a diffuser in the discharge 25 orifice which will break up or diffuse the stream issuing from the end of the nozzle and to provide a valve for controlling the stream flow and which seats on the peripheral edge of the nozzle, the stream flow 30 striking the face of said valve at an angle when the valve is unseated.

With the above mentioned and other objects in view the invention consists in the novel construction and combination of parts 35 hereinafter described, illustrated in the accompanying drawings and pointed out in the claims hereto appended; it being understood that various changes in the form, proportion, size and minor details of construction within the scope of the claims may 40 be resorted to without departing from the spirit or sacrificing any of the advantages of the invention.

To more fully comprehend the invention, 45 reference should be had to the accompanying sheet of drawings wherein—

Figure 1 is a view of a closet flushing tank, disclosing the water inlet and outlet, the ball operated inlet valve and the mechanism 50 for controlling the outlet valve. Fig. 2 is a sectional view of the water inlet disclosing my improved inlet valve and the diffusing means in the inlet nozzle.

Referring more particularly to the draw-

ings, wherein like characters of reference 55 designate corresponding parts throughout the several views—1 indicates a suitable flushing tank provided with the usual cover 2. A water inlet pipe 3 extends upwardly through the bottom of the tank and carries 60 at its upper end a contracted outlet or nozzle 4 having an outwardly beveled wall 4^a. The nozzle is surrounded by a casing 5 which rests on an annular flange 6 and is secured thereto by the screws 6'. A spider 4' is 65 mounted in the discharge nozzle 4, and the same receives the shank 4² of a baffle or diffuser which is positioned centrally within the discharge nozzle and carries at its end an enlarged head 4³ having a flat underface 4⁴. 70 The head 4³ of the diffuser is in a plane slightly below the edges of the discharge orifice of the nozzle so that the stream issuing from the nozzle will be deflected and strike the surface of the hereinafter described valve 75 at an angle. Extending vertically through the casing is a valve stem 7 carrying at its lower end a plate 8, to the peripheral edge of which is threaded the upper portion of the ring 9, which is formed with an in- 80 wardly projecting annular flange 10, having an outwardly beveled annular inner lower wall 11. A packing 12 preferably of leather is held between the flange 10 and the lower 85 surface of the plate 8, and said packing is adapted to rest on and close the contracted discharge nozzle of the inlet pipe. By providing the valve with the outwardly and downwardly beveled annular wall 11, the 90 water issuing from the nozzle 4 in an inverted conical stream, owing to the action of the diffuser thereon, will strike the packing 12 at an angle, and as the valve is opening or closing, will be deflected radially from the nozzle, and the force thereof 95 against the valve will be dissipated angularly from the nozzle, and will not be forced back onto the on-flowing stream which causes the valve to pound when closing.

The casing 5 is formed adjacent its lower 100 end with an opening 13 into which is threaded one end of a filler pipe 16 leading into the tank.

A flushing pipe 17 leading to the closet bowl also communicates with and opens at 105 its upper end into the bottom of the tank 1, and said pipe is controlled in the usual manner by the ball valve 18 carrying a stem

19, which coöperates with a member 20 connected to a pivoted crank arm 21 operated by the pivoted handle 22.

A bowl filling connection 23 leads from 5 the casing 5 into a larger pipe 24 which opens into the flushing pipe 17 below the ball valve 18.

The valve stem 7 is operated to raise and lower the valve by the usual mechanism, 10 which consists of the float 25 carried by a rod 26 connected at one end to a crank arm 27, pivoted to a bracket 28 carried by the valve casing 5, and said crank arm is pivotally connected by a link 29 to a lever 15 30 pivotally mounted on a support 31, and one end of said lever extends through and operates in a slot 32 in the valve stem 7.

By providing the diffuser with a head having a flat under surface, the column of 20 water passing through the nozzle will strike the flat under-surface of the head and will be directed thereby against the inner periphery of the nozzle and will issue therefrom in the form of an inverted cone.

25 It is to be understood that my improved diffuser may be applied to any suitable form of nozzle and to types of structures wherein there is employed a type of valve which when closing the discharge orifice of the nozzle fits over the end thereof.

Having thus described my invention what I claim and desire to protect by Letters Patent is:—

1. A water inlet for flushing tanks or the like, consisting of an inlet pipe extended 35 within the tank and connected to a source of supply under pressure, a nozzle on the discharge end of said pipe provided with a discharge orifice having an outwardly beveled interior end wall, a valve of greater 40 diameter than the discharge orifice of said nozzle, and adapted to seat thereover to close the same, means for mounting said valve, a packing carried by said valve for 45 contacting with the discharge end of said nozzle, a downwardly extending annular wall surrounding said packing and formed with an outwardly and downwardly beveled interior surface for directing the issuing 50 stream, externally of the sides of said discharge opening, a diffuser in the outlet ori-

fice of said nozzle for breaking the stream issuing therefrom and coöperating with the beveled wall of the discharge orifice for directing a portion of the same against the 55 beveled surface of said ring, and means for raising and lowering said valve relative to the discharge end of said pipe.

2. A valve structure of the class described, comprising a discharge nozzle having an 60 inwardly beveled wall surrounding the outlet orifice therein, a valve for fitting over and closing the discharge end thereof and of a diameter to extend beyond the edges of the nozzle within the path of the issuing stream and coöperating with said beveled wall for directing the stream flow issuing from said nozzle onto said valve at an angle 65 to the face thereof.

70 3. A valve structure of the class described, comprising a discharge nozzle, a diffuser within said nozzle comprising a shank positioned centrally of said nozzle and having at its outer end an enlarged head lying in 75 substantially the same plane with the surface of the discharge end of the nozzle, and a valve for fitting over the end of the discharge nozzle and of a diameter larger than the nozzle for controlling the stream issuing 80 therefrom.

4. A valve structure of the class described, comprising a discharge nozzle having an outwardly flared discharge orifice, a diffuser within said nozzle comprising a 85 shank removably positioned centrally of said nozzle and provided at its outer end with an enlarged head having a substantially flat under surface and lying in substantially the same plane with the surface 90 of the discharge end of the nozzle, and a valve for fitting over the end of the discharge nozzle and of a diameter greater than the same for controlling the stream issuing therefrom.

95 In testimony whereof I have signed my name to this specification in the presence of two subscribing witnesses.

BENJAMIN F. GABLE.
